ELECTRIC LOCK

Lucien R. Baril, River Edge, and Joseph Ulric
Baril, Livingston, N. J.

Application February 16, 1933. Serial No. 657,128

7 Claims. (Cl. 70—50)

Our invention relates to electrically operated locking and unlocking means for doors or windows of a dwelling or building and for any and all purposes for which it may be employed, and is especially designed for simultaneously locking and unlocking both the upper and lower sash of a window, although either or both sashes of the window may be closed without operating the lock electrically.

10 The prime object of the invention is to provide simple, durable, economical and thoroughly efficient electrically operated means disposed within the casing of the doors or windows so as to lock or unlock said means by making the proper contact from any safe and convenient point, such as the opposite side of the room from said doors or windows, by any authorized person desiring to lock or unlock the doors or windows.

15 A further object of the invention is to provide means so associated with both the upper and the lower sash of a window that, after either sash shall have been lowered or raised for ventilation purposes, both sashes may be simultaneously locked in their adjusted position by making the proper contact by means of a push button or any suitable switch.

20 Another object of the invention is to so construct the latch bolt with relation to means secured to the edge of each window sash that, when the sashes shall have been adjusted to any desired position and locked in such position, it will be impossible for any person seeking unauthorized entrance through the window by the raising of the lower sash, or the lowering of the upper sash, but both sashes may be entirely closed without operating any means electrically.

25 Further objects of the invention are to so construct our improved locking and unlocking means that such means may be disposed within a suitable metallic casing, and connected by suitable wires to the lighting circuit of a building and to form a part of the regular wiring of the building, the said locking and unlocking means may be successfully operated by merely pushing a button suitably located at any convenient point, and to associate said means with a lighting circuit adapted to operate a pilot light 30 to indicate when the door or window is locked or unlocked.

35 The foregoing and such other objects as may appear from the ensuing description are accomplished by the combination, arrangement, construction and location of the several parts here-

inafter more fully described and particularly pointed out in the claims appended hereto, and illustrated in the accompanying drawings, it being understood that slight changes in the precise form, proportions and minor details of the construction may be resorted to without departing from the spirit or sacrificing any of the advantages of the invention.

40 In the accompanying drawings forming a part of this specification it will be seen that:

45 Figure 1 is a plan partly in section illustrating the means embodying our invention, showing said means in its unlocked position.

50 Figure 2 is a detail partly in plan and partly in sectional elevation, showing the latch bolt in engagement with a window sash.

55 Figure 3 is an elevation partly in section, showing the locking means in locking engagement with the sashes of a window, showing said sashes in their partly lowered and raised positions, and

60 Figure 4 is a cross section taken in the plane of the dotted lines 4—4, Fig. 1, showing in section a portion of the window sashes broken away.

65 In the embodiment of our invention as illustrated, it will be seen that the numeral 1 designates a metallic casing suitably disposed within the casing of a door or window, said casing being provided with vertically disposed partitions 2 and 2' and laterally disposed partitions 3 and 3' extending from the partition 2' to the inner side wall 4 of said casing, the partitions and side walls being formed from a single piece of metal. Suitably secured within the casing and between the partitions 2 and 2' are two electromagnets 5 and 6, one adapted to force the latch bolts into their locked position and the other to withdraw the latch bolts into their unlocked position through the medium of the means hereinafter described.

70 Disposed intermediate of the two electro-magnets is a member 8 formed of a single piece of metal formed with a large central portion 9 adapted to slidably engage the inner face of each of the partitions 2 and 2' and formed through said central portion 9 is a diagonally arranged slot 10 terminating with a slightly upwardly curved formation at one end thereof, and at its other end with a slightly curved downward formation, said curved formations serving to lock and maintain the latch bolts in their unlocked and locked positions, respectively, and formed within said central portion 9 is a cavity or recess for the reception of the latch bolt operating member 12, said member extending in-

wardly and provided with a lateral extension 13' at each side of its headed portion 14 and terminating with a narrowed inwardly extended portion 15 adapted to suitably separate the locking and unlocking latch bolts 16 and to engage the headed portion 14' thereof, while through the upper end of the headed portion 14 of the operating member 12 is suitably secured a pin 17 which projects from each side of said headed portion and is adapted to engage with the slot 10, and formed integral with each end of the central portion 9 is a plunger 18 which forms the movable cores for the electro-magnets 5 and 6. Connected to an opening formed 10 through the partition 2 and an opening through the outer wall of the casing 1 is a sleeve 19 in the outer end of which is fitted a screw threaded plug member 20 and at its inner end portion is disposed a metallic ball 21 with a coiled spring 21' disposed between the plug member and said ball, said ball being adapted to be seated in a semicircular recess formed near each end portion of the member 8, shown by dotted lines, and serving to secure said member at each end 20 of its movement, and thereby prevent accidental movement of said member 8 in either direction, as shown in Fig. 1.

It will be perceived that a coiled spring 22 is disposed between the extensions 13' and the upper end or headed portion 14' of each of the locking and unlocking latch bolts 16, as is clearly shown in Figs. 2 and 4.

It will be observed that an opening is formed through the metallic casing through which are passed the wires 24 and 25 connected with the electrical source, said wires being suitably connected with the locking electro-magnet 5 and the unlocking magnet 6, so that when it is desired to lock a door or window it is simply necessary to push one of the buttons 27 which will energize the locking magnet 5, thus causing the member 8 and its cores to move or slide downwardly, thereby causing the latch operating member to force the latch bolts 16 into their locked position, which will be readily understood, and when it is desired to unlock the latch bolts press the other push button electrically connected with the unlocking magnet, thereby causing the member 8 to move in the opposite direction to withdraw the latch bolts.

When it is desired to use a pilot light in connection with our electrical locking and unlocking means, a light circuit is used through the wires 28 and 29 leading to an incandescent lamp 30, and to the electrical contact 31, formed by placing an insulation plug 32 at the end of one of the magnet plungers to which plug is secured a metallic member 33 adapted to close the circuit through the contact 31 and light the lamp to indicate that the doors or windows are in locked condition, as shown in Figs. 1 and 3.

It will be understood that our improved locking and unlocking means may be employed for all purposes for which it may be utilized, in connection with or without any light indicating means.

By reference to Fig. 3 of the drawings it will be seen that the window frame 34 is broken away to show the casing 1 containing the locking and unlocking mechanism suitably disposed within said frame, and showing one of the window sashes 35 in a lowered position and the other sash in a raised position, while the latch bolts 16 are shown in their locked position with relation to the said sashes, with the push buttons ar-

ranged adjacent the window frame and the indicating electric light disposed above the window frame.

Having thus described our invention, what we claim and desire to secure by Letters Patent is:

1. Electric locking and unlocking means of the character described, comprising a casing for the reception of said means, integral vertically disposed partitions formed within the casing, a pair of electro-magnets secured between the vertical partitions, reciprocating means disposed between and in contact with said partitions forming a core for each of said magnets, and latch bolts disposed between laterally extended partitions operated by means connected to the said reciprocating means.

2. Electric locking and unlocking means for window sashes of the character described, comprising a casing disposed within a window frame for the reception of said means, a pair of electro-magnets secured within the casing, integral reciprocating means disposed intermediate of the magnets forming the core of each magnet, and means connected with the reciprocating means for simultaneously locking both window sashes by pressing a contact push button.

3. Electric locking and unlocking means for windows, comprising a casing disposed within the window frame adjacent to the window sashes, a pair of electro-magnets secured within the casing, an integral slidably disposed member intermediate the magnets forming a core for each magnet and provided with a central diagonally arranged slot having a curved formation at each end thereof, and means connected with the slidable member and said slot for simultaneously operating the latch bolts to lock and unlock both sashes of the window by pressing a push button.

4. Electric locking and unlocking means of the character described, comprising a casing for the reception of said means, a pair of electro-magnets within the casing, a reciprocating slide within the casing formed from a single piece of metal forming the core of each magnet and with a central rectangular portion, a diagonally disposed slot formed through said rectangular portion of said slide, said slot being formed with a curved formation at each of its ends, and means connected to the slide and slot for operating the locking and unlocking means by pressure on a push button.

5. Electric locking and unlocking means of the character described, comprising a casing disposed within a window frame, vertically disposed partitions within the casing formed integral therewith, a pair of electro-magnets secured between the partitions within the casing, a reciprocating member disposed intermediate the magnets forming the core of each magnet and provided with a central rectangular portion, a diagonally disposed slot formed through the rectangular portion of said member, said slot being formed with a curved formation at each end thereof, and means connected with the member and said slot for simultaneously locking window sashes in their adjusted positions by the operation of a push button.

6. Electric locking and unlocking means of the character described, comprising a casing, a pair of electro-magnets secured within the casing, a reciprocating member formed with a rectangular central portion intermediate the magnets and forming the core of each magnet, an angular slot formed through the rectangular

portion of the member with a curved formation at each end of said slot, and means connected to the central portion of said member and within the slot for operating the latch bolts to lock and unlock by the movement of the said member to and fro by the operation of a push button.

7. Electric locking and unlocking means of the character described associated with window sashes, comprising a casing for the reception of 10 said means disposed within a window frame associated with means secured to said sashes for the reception of the latch bolts, a pair of elec-

tro-magnets secured within the casing, a reciprocating member disposed between said magnets formed of a single piece of metal having a rectangular central portion with an angular slot having a curved formation at each of its ends formed therethrough, said member forming the core of each magnet, and means connected with said central portion and slot for simultaneously operating the latch bolts to lock and unlock the sashes by the operation of a push button.
